UNITED STATES PATENT OFFICE.

HOWARD H. SAWYER, OF PORTLAND, OREGON.

WATER-MOTOR.

1,218,900.

Specification of Letters Patent. Patented Mar. 13, 1917.

Application filed March 28, 1916. Serial No. 87,307.

To all whom it may concern:

Be it known that I, HOWARD H. SAWYER, a citizen of the United States, residing at Portland, in the county of Multnomah, State 5 of Oregon, have invented certain new and useful Improvements in Water-Motors; and I do hereby declare the following to be a full, clear, and exact description of the invention, such as will enable others skilled 10 in the art to which it appertains to make and use the same.

This invention relates to improvements in water motors.

One object of the present invention is to 15 provide a novel raising and lowering means for the mechanism to accord with the rise and fall of the tide.

Another object is to provide an improved construction of vane in the power chain 20 whereby simplicity will be combined with cheapness.

Another object is to improve and simplify the construction of the power chain whereby the vanes can be more easily and 25 quickly set into or removed from the chain.

Other objects and advantages will be apparent from the following description when taken in connection with the accompanying drawing.

30 In the drawing:

Figure 1 is a vertical longitudinal sectional view through my improved water motor.

Fig. 2 is a detailed perspective view of 35 one of the raising and lowering means for the mechanism.

Fig. 3 is a perspective view of a section of the power chain.

Fig. 4 is a perspective view of a section 40 of the power chain, showing a modification thereof.

Referring particularly to the accompanying drawing, 10 represents a pair of piers, spaced a suitable distance apart, and arranged 45 respectively upstream and downstream. Between these piers is a third pier 11. Formed vertically in each of the piers 10 is a well 12, to the sides of which are secured the channel members 13, forming 50 guides, as will be later explained. These channel members are embedded in the walls of the wells, the piers being formed of concrete, and are anchored by means of bolts 14, which have their heads countersunk into 55 the members and lying flush with the faces of the channel members. In the lower por-

tion of each of the wells is disposed a block 15 to which is secured a vertically extending rack bar 16, said bar extending upwardly from the top of the pier, and engaging with a pinion 17 carried by a shaft 18 and mounted in a bearing bracket 19 at the top of the pier. One end of the shaft carries a hand wheel for rotating the shaft to accomplish the raising and lowering of the block. Secured to the upper side of the block 15 is a second block, which is divided, as shown at 20, and formed with a transverse opening or bore 21 in which is received one end of a shaft 22. The parts described with respect to the well are duplicated at the other side of each well, so that the shafts 22 are supported at both ends therein. Recesses 23 are formed in the outer faces of the blocks, and in said recesses are mounted the 70 rollers 24, which serve to facilitate the upward and downward movements of the blocks in the guides, before mentioned at 13. Suitable brackets 25 are mounted at the top of the pier 11, to support a shaft 26, on which are mounted the sprocket wheels 27. On the ends of the shafts 22 are also mounted sprockets 28, and engaged around the sprockets 27 and 28 are chains 29. These chains are made up of the parallel plates 30, 80 and the transverse bolts 31, arranged in sections, and between each pair of sections are disposed vertically disposed vanes or blades 32. These vanes are formed of metal, and have their upper and lower edge portions 90 turned rearwardly as clearly shown at 33. The upper portions of the sides of the vane are cut as shown at 34, and the portions bent downwardly and rearwardly, as shown at 35, and at right angles to the vertical plane 95 of the vane. Secured to the upper face of each of the rearwardly turned portions 35 is a plate 36, having its front and rear ends rolled, as shown at 37. The ends of the plates 30 at the adjacent ends of the chain 100 sections, are disposed at the ends of the rolled portions of the plates 36, and bolts 38 passed through the plates and rolled portions. Thus the blades or vanes are held in proper positions between the sections of 105 the chains, for action thereagainst of the water current of the stream.

In Fig. 4 is shown a modified form of the vane, in which the body is formed of a single board or wooden strips 39 secured together 110 at their ends by the metal strips 40. The intermediate portions of these metal strips

are twisted to lie in horizontal planes, as shown at 41, and then the plates 42, similar to the plates 36 are secured to the lower faces thereof. The chain sections are then secured to the rolled ends 43 of these plates, in a manner similar to that of the first form.

The power is adapted to be taken from the shaft 26 to a suitable point on the shore.

It will thus be seen that the current of the stream will strike against the vanes and drive the chains, which in turn will rotate the shaft 26, through the means of the sprocket wheels carried thereby.

What is claimed is:

- 15 1. In a water motor, piers, vertically adjustable shafts mounted on the piers, sprockets carried by the shafts, additional piers disposed between the first-named piers, a shaft carrying sprockets mounted on the additional piers, power chains engaged around the sprockets, and vertically disposed vanes secured at intervals in the chains, said vanes each comprising a metal plate having its upper and lower edge portions curved rear-

wardly, rearwardly extending integral members formed at the sides of the vane, plates having their ends rolled into tubular form secured to the said members, and bolts engaged through the tubular portions and the adjacent links of the chains.

2. A water motor including an endless traveling element comprising a plurality of vertically disposed plates each having a tab formed at one end and on the upper portion thereof, the tab being bent to extend at right angles to the plane of the plate, a plate secured to the tab and extending forwardly and rearwardly of the first-named plate, the ends of the second-named plate being rolled into tubular form, bolts disposed in the tubular portions, and links engaged on the bolts at the ends of the tubular portions.

In testimony whereof, I affix my signature, in the presence of two witnesses.

HOWARD H. SAWYER.
